ELECTRONIC TUBE

Albert G. Thomas, Lynchburg, Va.

Original application July 3, 1939, Serial No. 282,733. Divided and this application May 15, 1943, Serial No. 487,175

7 Claims. (Cl. 250—27.5)

1

This invention relates to electronic tubes, and is a division from my abandoned application, Serial No. 282,733, filed July 3, 1939.

An object is to provide a tube to produce high frequency pulsations or oscillations.

Another object is to provide a high frequency tube of simple construction.

A further object is the provision of a tube capable of producing oscillations of extremely high frequency.

Other objects will appear in the specification.

In the drawings:

Figure 1 is a sectional side elevation of an ultra high frequency tube with hollow cathode construction.

Figure 2 is a sectional side elevation of an ultra high frequency tube with a hollow oscillator.

Figure 3 is a side sectional elevation of an ultra high frequency tube with in-built resonant circuit.

Figure 4 is a side sectional elevation of a hollow electronic resonator or oscillator.

Figure 5 is a side sectional elevation of another hollow oscillator which can be used with one or more of the previously designated tubes.

Figure 6 is a side sectional elevation of another form of hollow electronic oscillator.

In Figure 1, tube 1 has anode 2, grid 3 and cathode 4 which is shown as indirectly heated but which can be merely a hot wire, a photo emissive surface, or otherwise. Metal housing 5, preferably of cylindrical shape, is placed around cathode 4 and may be insulated from it. Opening 6 is provided in the face of housing 5 to allow electrons to pass out toward anode 2. The interior surface of housing 5, or areas of it, is preferably covered with barium oxide or similar substance that will emit a copious supply of electrons when heated. Housing 5 may be heated from cathode 4 by means of surrounding resistance coil 7 with leads 8 and 9 brought out of the tube. In the latter event the magnetic field produced by coil 7 will assist in directing electrons toward opening 6, if the various dimensions and variables are properly chosen.

Cathode 4 can be of small area to form practically a beam of electrons directed toward opening 6. Suitable accelerating and beam focussing rings can be placed inside housing 5 if desired, the leads for which can be brought out by means of insulation bushings. Grid 3 can be positively charged to assist in pulling electrons out of opening 6. This grid may consist of a very small area or of a point electrode if desired.

Heating of housing 5 will cause a cloud of elec-

2

trons to exist, through which the beam from cathode 4 will pass. The passage of the beam of electrons through the electron cloud will cause very rapid oscillations of the cloud similar to air vibrations in a whistle. Therefore a rapidly pulsating beam of electrons will issue from opening 6 and will travel to anode 2. High frequency current can therefore be generated in this manner. The frequency of fluctuation will depend upon the dimensions of housing 5, the density of the cloud, and upon the beam speed. An electron gun can be substituted for cathode 4 so that high speed electrons will be projected into the cloud. A number of perforations 6 may be employed instead of one.

A further tendency to rapid oscillation will occur since the electron cloud will tend to crowd through opening 6 due to mutual electron repulsion. This effect is similar to steam issuing from an orifice. If desired, the outside of housing 5 may also be coated to emit electrons so that the jet of electrons issuing from opening 6 will be discharged into a cloud of electrons in tube 1, which cloud will be set into rapid vibration to modulate the output current at high frequency. The actual tube 1 may be of tubular shape or any convenient shape. Housing 5 may be grounded or made positive relative to cathode 4.

In Figure 2, tube 10 has anode 11 and cathode 12. Electron accelerating and beam forming elements 13 and 14 are placed at progressively higher potentials relative to cathode 12 and have central openings as shown so that a beam of electrons is shot through central openings 15 and 16 in opposite faces of cylindrical housing 17. The interior of this housing is coated with barium oxide, thorium, or other material to produce a copious supply of electrons when the housing is heated by means of surrounding resistance coil 18 which has exterior leads 19 and 20.

The electron cloud in housing 17 will therefore be set into rapid vibration by the passing beam and the beam will consequently be modulated at high frequency before it strikes anode 11. A high frequency output will result.

If desired, rings 21 and 22 may be placed near openings 16 and 15, and can be charged slightly negative with respect to housing 17 in order to prevent the escape of excessive numbers of electrons. Resistance 18 may be wound to produce a magnetic field or not, as desired. Housing 17 may be grounded to supply electrons and to prevent the building up of excessive charges, or it may be made positive relative to cathode 12.

In Figure 3, tube 23 has anode 28 and cathode 24. Accelerating anode 25 with central opening for defining a beam of electrons is positively charged relative to cathode. This anode may also be used as a control grid if desired. Cylinder 26 is charged at higher positive potential and serves to accelerate and focus the electron beam. Still another positively charged anode 27, with small central opening, may be used to accelerate, focus, and define the beam so that it will pass through small annular rings 29 and 30 which are connected in series with small condenser 31 and inductance 32 as shown. Inductance 33, with exterior leads 34 and 35, is in inductive relation to inductance 32. The rings 29 and 30 can be placed sufficiently close together so that the capacity between them will make condenser 31 unnecessary, in which case inductance 32 and the capacity between the rings will form a resonant circuit. If then the electron beam is broken up into groups of electrons and if these groups pass through rings 29 and 30 at intervals so that oscillatory currents in the tuned ring circuit are properly reinforced, an extremely rapid oscillatory current will be induced in coil 33 and can be taken off leads 34 and 35.

The oscillating currents in the ring circuit will tend to modulate the anode current so that high frequency can also be taken off the anode circuit. This modulating effect may be sufficient to form a resonant condition which will keep sustained oscillations in the ring circuit, but the prior chopping of the electron beam into groups will certainly perform this function. The beam may be broken up into groups in a number of ways, two possibilities of which are shown in the tubes of Figures 1 and 2. Inductance 32 may be coupled to the grid circuit so that the beam will be modulated at the frequency of oscillation of the ring circuit. Care must be taken so that the time of transit of the electron groups through rings 29 and 30 will be in keeping with the natural period of oscillation of the ring circuit so that a resonant condition will exist.

Figure 4 shows a small electron oscillator tank 36 with opening 37. The interior of this tank is coated with barium oxide or the like and the tank can be heated in any desired way so that a cloud of electrons will be formed inside the tank. This cloud will tend to escape through opening 37 and if a beam of electrons is directed across the opening as indicated by the arrow, the electron cloud in the tank will be set into very rapid vibration on the same principle that causes air in a whistle or organ pipe to be set into oscillation. The oscillating cloud will then cause a fluctuating ejection of electrons out of opening 37 to modulate the electron beam at very high frequency. This tank may be used in place of element 47 in Figure 2. It may be grounded if desired and may be surrounded by a heating coil, or may be equipped with an interior filament or lamp to liberate photo electrons. The exterior electrons may be collected by the usual anode or by an additional positively charged or grounded element. Such an additional element is shown at 38 and the high frequency circuit may be established between tank 36 and element 38 as terminal cathode and anode respectively.

In Figure 5 tank 39 has central aligned openings 40 and 41 through which a beam of electrons may be passed. Plates 42 and 43 are covered with electron emissive material and are suitably heated. These plates may be insulated from tank 39 and may be connected at one point by in-

ductance 44 and at another point by condenser plates 45, with suitable wires. Plates 45 are placed so that the electron beam will pass between them and set the interior circuit into oscillation to modulate the beam at high frequency. Plates 45 may be covered with electron emissive material instead of plates 42 and 43, if desired.

Figure 6 shows tank 46 with aligned openings 47 and 48, off-set as shown so that an unbalanced path for the interior electrons will exist. These oscillating electrons will then not be so liable to cancel the effect of each other as if the beam passed through the center.

I have shown and described electronic tubes which I consider to be based upon novel principles. Many changes of detail can obviously be made without departing from the broad concepts I have disclosed.

What I claim is:

1. An electron discharge tube comprising, a cathode, an anode, a hollow element intermediate said cathode and anode and having opposed openings therein facing respectively said cathode and said anode, and means within said tube and adjacent said hollow element for heating said hollow element.

2. An electron discharge tube enclosing a cathode, an anode, a hollow element having opposed openings therein facing respectively said cathode and said anode, conductive material of relatively low work function on a portion of the interior surface of said hollow element, and means adjacent said hollow element for heating said element.

3. An electron discharge tube enclosing, a cathode, an anode, a hollow element having opposed openings therein facing respectively said cathode and said anode, conductive material of relatively low work function on a portion of the interior surface of said hollow element, means adjacent said element for heating said element, and a control member adjacent one of said openings.

4. An electron discharge tube enclosing, a hollow element having opposed openings therein, means within said tube and aligned with said hollow element for forming a beam of electrons and for directing said beam through said openings, and means within said tube and adjacent said element for heating said element.

5. An electron discharge tube enclosing, a hollow element having opposed openings therein, means within said tube and aligned with said hollow element for forming a beam of electrons and for directing said beam through said openings, conductive material of relatively low work function on a portion of the inner surface of said element, and means within said tube and adjacent said element for heating said element.

6. An electron discharge tube comprising, a hollow conductive element having opposed openings therein, means within said tube for forming a beam of electrons and for directing said beam through said openings, material of relatively low work function on a portion of the inner surface of said element, and a coil for carrying current around said element, the axis of said coil being substantially parallel with the path of said beam.

7. An electron discharge tube comprising, a hollow element having an opening therein, means within said tube and aligned with said opening for forming a beam of electrons and for directing said beam through said opening, material of relatively low work function on a portion of the interior surface of said element, and means within

said tube and adjacent said element for heating
said element.
